FIG. 1

FIG. 2

FIG. 3

FIG. 4FIG. 5FIG. 6

FIG. 1 is a top plan view of a combined gas tank and horn trumpet for a fire alarm or the like showing my new design.

FIG. 2 is a left side elevational view thereof.

FIG. 3 is a rear elevational view thereof.

FIG. 4 is a bottom plan view thereof.

FIG. 5 is a front elevational view thereof.

FIG. 6 is a fragmentary right elevational view thereof, partly broken away to show the internal configuration of the horn trumpet.

The broken line showing of the accessory equipment in FIGS. 1-5 is for illustrative purposes only.

I claim:

The ornamental design for a combined gas tank and horn trumpet for a fire alarm or the like, as shown and described.
